UNITED STATES PATENT OFFICE.

IRA J. KUERT, OF LOS ANGELES, CALIFORNIA.

ADJUSTABLE AND INTERCHANGEABLE FORM FOR HOLLOW WALL CONSTRUCTION.

Application filed December 29, 1922. Serial No. 609,599.

To all whom it may concern:

Be it known that I, IRA J. KUERT, a citizen of the United States, residing at Los Angeles, in the county of Los Angeles and 5 State of California, have invented new and useful Improvements in Adjustable and Interchangeable Forms for Hollow Wall Construction, of which the following is a specification.

10 This invention relates to adjustable and interchangeable forms for hollow wall construction, and it is an object of the invention to provide a collapsible interior form for hollow cement walls. Another object of the 15 invention is to provide a substantial, practicable and reusable metal hollow core or form structure for use in the erection of concrete walls. A further object is to provide a hollow wall form or core consisting of side 20 panel elements and overlapping end elements combined with means for expanding and contracting the panel elements to set them in position in preparing for casting and to facilitate the withdrawal of the inner 25 form after the wall has set.

Other objects and advantages will be made manifest in the following specification of an embodiment of the invention illustrated in the accompanying drawings, wherein—

30 Figure 1 is a vertical transverse section through a wall built upon the set up internal hollow form.

Fig. 2 is a vertical transverse section through the wall showing the form in collapsed position and as being withdrawn from the hollow wall.

Fig. 3 is a perspective of fragments of elements of the contracting apparatus.

Fig. 4 is a plan of the distended or expanded form.

Fig. 5 is a side elevation of the expanded form.

Fig. 6 is a plan of the transverse panel contracting means.

Fig. 7 is a plan of the longitudinal and transverse contracting means.

Fig. 8 is a detail of a pulling hook.

The present form consists of a unit structure formed of sections or panels preferably 50 of sheet metal which, while they may be of uniform length to obtain a unit of given height, may be of various width so that by the proper selection of panels of different width, a hollow internal form for making a hollow concrete wall W may be produced.

In Figs. 4 and 5 a mold unit is shown as consisting of a number of side panels 2, 3, 4 and 5 of suitable length and width and which are adapted to form one side of a core or under form with the outer face substantially in a common plane as nearly as may be obtained, allowance being made for the slight offset produced by the overlapping or contiguous vertical edges of the panels 2, 3, 4 and 5. It is to be understood 60 that any number of such panels may be utilized in the formation of a unit form and directly opposite to each of the panels here designated as 2, 3, 4 and 5 are companion panels 2^a, 3^a, 4^a and 5^a, these obviously respectively having widths equal to their co-ordinate panels, all for facilitating manufacture, erection and use of a unit form.

To the end panel elements of the two walls of the unit there are secured transverse end closure forming elements which are here shown as angle strips 6 and 7 respectively secured to the end panels 2 and 5 so as to present inwardly turned webs or flanges 6^a and 7^a to overlap inwardly turned 70 flanges 8^a and 9^a of corner elements 8 and 9 secured to the end sections 2^a and 5^a. The overlapping flanges 6^a, 7^a, 8^a and 9^a are designed to shift freely on each other to form end closures to prevent infiltration of 80 cementitious material into the chambers of the forms, a series of which is adapted to be constructed by abutment of one form against another endwise in a row in a given position for construction of a wall.

Meeting adjacent edges of the upright panels sections are overlapped to form a sufficiently tight joint, and means are provided for bracing the side panels of the form in extended position and for contracting the side panels after the concrete wall has hardened.

Such bracing and contracting means includes a series of contracting devices each of which has a vertically extending bar 10, 100 Figs. 1 and 2, of a length about equal to the height of the form unit, and at suitable spaces along the bar are pivots 11 from which are extended alternately in opposite direction a series of links 12 whose outer ends 105 are pivotally connected at 13 to parallel strips 14 and 15 of angle iron, preferably. The angle iron strips 14—15 are thus capable of being relatively separated in parallel position by movement of the push bar 110

10 in one direction and are adapted to be contracted, as shown in Fig. 2, by a movement of the bar in an opposite direction.

In the construction of a collapsible unit 5 form of the present type, the parallel angle iron strips 14 and 15 are set with flanges inwardly directed toward each other in a common plane as shown at 14^a and 15^a, Fig. 6, and to these inwardly disposed flanges 10 are connected the several expanding and contracting toggle links 12 along contiguous faces. The opposite faces of the flanges 14^a and 15^a are secured by top rivets 16 and bottom rivets 17 to inwardly directed flanges 18 and 19 of angle strips 18^a and 19^a which are secured permanently to contiguous end portions of respective side panels such as 2, 2^a, 3, 3^a, etc., as above identified. By connecting the flanges 14^a and 15^a only at their 20 top and bottom ends to the fixed flanges 18 and 19 of the side forming panels, it will be seen that the rivets 16 and 17 may be quickly driven out and the contracting means utilized in combination with other panels 25 of different length and width in the construction of different sizes of unit forms.

As clearly shown in Fig. 4, as many of the transversely connected and vertically arranged sets of expanding or contracting devices 30 may be employed as is necessary in a unit form of given length, and in the erection of a given form the push bars 10 are adapted to be driven downwardly so as to spread the angle strips 14—15 and therewith 35 the fixed angle strips 18^a—19^a and the side forming wall or panel members connected thereto. Conversely, when it is desired to contract a form after a wall W has been 40 poured and has set, then the several bars 10 are pulled with the result that the links 12 and their attached angle strips are contracted. This is clearly shown in Fig. 2 and 45 may be accomplished by any suitable form of pulling tackle, here shown as including a hook 20 to engage in an eye in the upper end of the expanding and contracting bar 10 whereby these bars are first pulled up to 50 contract the form, and further hooks 20 having cover plates 21, Figure 8 are shown as connected to the form elements for supporting these and withdrawing the form from the hollow wall. The pulling and elevating tackle may be suitably supported as on a rail or guide bar 22.

55 To facilitate the contraction of the form and its removal from the cast wall, it is desirable that the form be so constructed that it can contract longitudinally as well as laterally, and such longitudinal contraction 60 may be secured by providing a set of the toggle-like links on each longitudinal wall of the mold at suitable points and so connecting these to contiguous wall panels that the connected wall panels can be drawn 65 edgewise as to each other and thus effect a

shortening of the form. In Fig. 7 there is shown in detail overlapping portions of panels 3^a and 4^a on one side and panels 3 and 4 on the other side of the form. To angle strips 18^a and 19^a, above referred to, 70 are attached a vertical series of links 12, and these links are attached to upright push or contracting bars 10^a, and from these links 12^a extend in the opposite direction and are attached to other angle strips 18^a 75 and 19^a shown as secured, for instance, on the panels 4 and 4^a. The contracting bars 10^a are arranged with their respective links 12 and 12^a to act with a pulling action for longitudinally contracting the form and are thus disposed at right angles to those of the toggle devices which are arranged transversely in the form and are adapted to contract the same laterally.

Since the contracting angle strips 14—15 85 are connected only at their upper and lower ends by rivets 16 and 17 to the contiguous form elements, it is desirable to provide a solid connection for the contracting action of the angle strips 14—15 about midway of 90 their length on the contiguous form elements, and such a positive action and means is clearly shown in Fig. 3 as including a lug 25 fixedly secured as on flanges 18 and 19 which are secured fixedly to respective wall 95 panels. The lug 25 turns inwardly across the edge of its respective flange into the path of the contiguous angle strip flange 15^a, for instance, so that when the contracting strips pull inwardly they will encounter the 100 lugs 25 and these will serve to take the pressure of the toggle mechanism and will pull inwardly the central portions of the form elements with a uniform movement 105 from top to bottom in collapsing the form. 110

For the purpose of obtaining a firm interlock of the toggle device in the expanded position, the pivot connections 11 of each push rod are designed to swing below a horizontal line passing through the pivots 13 at 110 the outer ends of the toggle links 12.

Preferably, the top of each of the forms is substantially closed to keep concrete or other material from falling into the form chamber during operations, and for this 115 purpose I provide a top structure which may consist of substantially flat cover plates 28 of suitable length and having along the parallel edges downward lips or flanges 29. A complementary set of the top plates 28 120 may be provided for each form, and the plates are, therefore, adapted to be nested in overlapping positions at the contiguous ends as shown in Fig. 5.

The toggle links 12 are provided at their 125 swinging ends with a plurality of apertures 12^a for the selective reception of pivot pins or connecting devices 11 passing through the pull and push bar 10. By this form of connection it is possible to utilize one set of 130

toggle links with the intermediate push bar 10 and the parallel angle strips 14 and 15 for forming forms of various effective widths, simply by the arrangement of the 5 pivots 11 in the desired apertures 12^a in the links. This form of connection provides a large range of adjustment in constructing a form.

Preferably, the toggle links 12 have stop 10 shoulders 12^b at their outer lower corners, and these shoulders are adapted to abut against the contiguous flanges when the toggles are swung to the approximately horizontal position and, therefore, prevent 15 the movement of the toggles downwardly to such an extent as to tend to again contract the side panels.

Further embodiments, modifications and changes may be resorted to within the spirit 20 of the invention as here claimed.

What is claimed is:

1. A unitary collapsible hollow wall form comprising, in combination, sectional side panels and inwardly and oppositely disposed end panels for respective side panels, toggle mechanism extending transversely between the side panels and attached thereto whereby the side panels may be erected in expanded form forming position and 25 whereby the side panels may be contracted after the cast wall has set, the side panels each being formed of relatively edgewise movable portions whereby the side panels can be contracted longitudinally, and toggle 30 means for longitudinally contracting the 35 form.

2. An adjustable and interchangeable form for hollow wall construction comprising substantially parallel side panels, angle 40 iron strips secured to the inside face of the panels and having inwardly projecting flanges, and form contracting means including sets of toggle devices, each toggle device including a pair of spaced angle iron 45 strips attachable to the inwardly projecting flanges provided on the panels, a push and pull bar for each toggle mechanism, and toggle links having inner ends connected to said push bar and having outer 50 bars connected to said angle strips whereby the form may be erected in expanded condition to form a chamber within a hollow wall as it is built and for contracting the form panels after the wall has been completed to a predetermined height along the form, the form 55 panels being constructed of sections adapted to be longitudinally contracted for shortening the form, and toggle mechanism connecting continuous edges of the form sections for contracting the same.

5. In a collapsible hollow form, oppositely disposed wall forming panels, and toggle mechanism connected to said panels for expanding and holding the same expanded or separated and for contracting the panels to collapse the form, said toggle mechanism including links pivoted at inner ends to a common thrust element and having stop shoulders at their outer ends to limit movement of each link in one direction when the form panels are fully expanded.

6. In a collapsible hollow form, oppositely disposed walls consisting of longitudinally adjustable sections, each of which sections is built up of interchangeable panels whereby the walls of the form may be made of any desired length by use of panels of different width in the said sections.

In testimony whereof I have signed my name to this specification.

IRA J. KUERT.

cluding sets of toggle devices, each toggle device including a pair of spaced angle iron strips attachable to the inwardly projecting flanges provided on the panels, a push and pull bar for each toggle mechanism, and toggle links having inner ends connected to said push bar and having outer bars connected to said angle strips whereby the form may be erected in expanded condition to form a chamber within a hollow wall as it is built and for contracting the form panels after the wall has been completed to a predetermined height along the form, the form panels being constructed of sections adapted to be longitudinally contracted for shortening the form.

4. An adjustable and interchangeable form for hollow wall construction comprising substantially parallel side panels, angle iron strips secured to the inside face of the panels and having inwardly projecting flanges, and form contracting means including sets of toggle devices, each toggle device including a pair of spaced angle iron strips attachable to the inwardly projecting flanges provided on the panels, a push and pull bar for each toggle mechanism, toggle links having inner ends connected to said push bar and having outer bars connected to said angle strips whereby the form may be erected in expanded condition to form a chamber within a hollow wall as it is built and for contracting the form panels after the wall has been completed to a predetermined height along the form, the form panels being constructed of sections adapted to be longitudinally contracted for shortening the form, and toggle mechanism connecting continuous edges of the form sections for contracting the same.

5. In a collapsible hollow form, oppositely disposed wall forming panels, and toggle mechanism connected to said panels for expanding and holding the same expanded or separated and for contracting the panels to collapse the form, said toggle mechanism including links pivoted at inner ends to a common thrust element and having stop shoulders at their outer ends to limit movement of each link in one direction when the form panels are fully expanded.

6. In a collapsible hollow form, oppositely disposed walls consisting of longitudinally adjustable sections, each of which sections is built up of interchangeable panels whereby the walls of the form may be made of any desired length by use of panels of different width in the said sections.
